United States Patent Office.

JEHU MITCHELL, OF NEWARK, OHIO.

Letters Patent No. 72,316, dated December 17, 1867.

IMPROVED WASHING-MACHINE.

The Schedule referred to in these Letters Patent and making part of the same.

TO ALL WHOM IT MAY CONCERN:

Be it known that I, JEHU MITCHELL, of Newark, in the county of Licking, and State of Ohio, have invented a new and useful Improvement in Washing-Machines; and I do hereby declare that the following is a full, clear, and exact description thereof, which will enable others skilled in the art to make and use the same, reference being had to the accompanying drawings, forming a part of this specification.

This invention relates to an improved washing-machine, and consists in the insertion of ribs in the end of the machine, between which, and a vibrating weighted dasher, provided with pounders alternating with said ribs, the clothes are squeezed and effectually washed and cleansed. In the accompanying drawings—

Figure 1 is a perspective view of my improved washing-machine, and.

Figure 2 is a vertical section thereof, at line R R of fig. 1.

Figure 3 is a detail side view of the dasher.

Figure 4 is an end view of the pounders thereof, and

Figure 5 is a detail side view of one of the end ribs.

Similar letters of reference indicate corresponding parts.

A is the box, of ordinary construction, except that the bottom, O, is an inclined plane, as shown by the dotted lines, fig. 1. D are standards, firmly secured to the sides of the box, and projecting above the same. These standards are connected above by the horizontal bar T, on which are hung the arms H H, in such manner as to swing without any lateral or side motion. From the other ends of the arms H is suspended the dasher-frame L by its cross-bar S. This frame consists of the side bars or pieces E, joined together at one end by the cross-bar G, and at its other end (which, when the dasher is in use, is within the box A,) by the cross-pieces J and P. Between the cross-pieces J and P is fastened a series of pounders or ribs, I, (at various points, and at equal distances apart from one another,) from one side of the frame to the other, the broad ends of the side bars E serving for the outside pounders. The ribs I are further secured by the cross-tie or bolt Q passing from one shaft E in the broad end, whereof one end of said bolt is secured through the whole of said ribs I, and has its other end secured in the other shaft E.

From the description above given of the manner in which the frame carrying the ribs I is hung to the posts D of the box A, it is manifest that it can be swung within the box A, towards and away from the end A' of said box, moving in a downward inclined direction upon the inclined bottom thereof, thus forcing the clothes within the box against such end. For a more effectual washing of the clothes such end is provided with a series of ribs, M, in positions corresponding to the spaces between the ribs I, and it may be observed that the resulting action is a squeezing one, which, while more effectually cleansing the clothes, is far less destructive of the fibre or of hard substances, such as buttons attached to said clothes, than ordinary washing-machines. The ribs M are covered by a cap, N, which prevents the water being thrown out when the lid C is removed.

To increase the power and facilitate the washing process, the frame L is weighted with the metal cross-bar F. A stop or cleat, V, fast to the bottom O, holds the dasher while the clothes are being removed, or the dasher can be drawn entirely out of the box, by drawing it to the front end thereof and tilting the pounders over the edge. K is a faucet, for running off the water.

Having thus described my invention, what I claim as new, and desire to secure by Letters Patent, is—

The frame L, hung by arms H H to bar T, when provided with ribs I I and weight F, in combination with the box A, having standards D, inclined bottom O, and stationary ribs M, all constructed, arranged, and operating as and for the purpose described.

The above specification of my invention signed by me, this 19th day of August, 1867.

JEHU MITCHELL.
